(57) **CLAIM**

The ornamental design for a front sensor housing, as shown and described.

DESCRIPTION

The present application is related to copending application Ser. No. 29/602,101, entitled Roof Sensor Housing; to application Ser. No. 29/602,117, entitled Fender Sensor Housing; and to application Ser. No. 29/602,110, entitled Rear Sensor Housing, each of which is filed concurrently herewith, the entire disclosures of which are incorporated by reference herein.

FIG. 1 is a front perspective view of a front sensor housing according to our design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front perspective view of the front sensor housing positioned on a first exemplary vehicle; and,

FIG. 9 is a front perspective view of the front sensor housing positioned on a second exemplary vehicle.

The broken lines shown in FIGS. 1-7 illustrate portions of the front sensor housing that form no part of the claimed design. The broken lines shown in FIGS. 8-9 illustrate portions of the front sensor housing and the exemplary vehicles that form no part of the claimed design.

The specific placement of the front sensor housing in FIGS. 8-9 on the exemplary vehicles are for illustrative purposes only.

1 Claim, 6 Drawing Sheets
